UNITED STATES PATENT OFFICE.

LAWRENCE L. NEEBE, OF WOODBURY, NEW JERSEY.

LOCOMOTIVE CROSSHEAD GUIDE.

Application filed December 13, 1926. Serial No. 154,590.

My invention relates to certain improvements in the cross-head guides for three-cylinder locomotives.

The object of the invention is to so construct the guides that they can be readily located in position and firmly secured to the cylinder structure of the locomotive and to two cross-ties which are mounted on the frame of the locomotive.

10 In the accompanying drawings:

Fig. 1 is a perspective view of sufficient of a three-cylinder locomotive to illustrate my invention;

Fig. 2 is a plan view;

15 Fig. 3 is a side view; and

Fig. 4 is a cross-sectional view.

The cylinder structure 1 has three cylinders 2, 2^a and 3, and three valve-chests 4, 4^a and 5 which connect with the cylinders and 20 with the steam supply and exhaust passages.

The frame 6 of the locomotive is of any suitable construction, and extending from one side member of the frame to the other side member are cross-ties 7 and 8 which 25 overhang the frame and support the guides 9 and 9^a, respectively, of the cross-heads 10 which are attached to the piston-rods of the side cylinders 2 and 2^a.

The guide 9^b for the cross-head 10^a which 30 is attached to the piston-rod of the central cylinder 3 is secured by a knee-plate 15 to the central portion of the cross-tie 7, which is nearest to the cylinders, and has a forward extension 11^b, which is secured by bolts 35 to a bracket 12^b on the head 13^b of the central cylinder.

The side guides 9 and 9^a are attached to both cross-ties 7 and 8 by bolts as shown, and each foot 7^a of the cross-tie 7 is secured by 40 bolts to a bar 14, which in turn is secured by bolts or other fastenings to brackets 12—12^a on the heads 13—13^a of the side cylinders.

The three guides are substantially the same 45 in cross-section as shown in Fig. 4, and are almost identical in form, with the exception that the central guide has an extension which is secured directly to the brackets on the cyl-

inders. This extension is omitted in the side guides as they are connected to the cylinder-heads by the bars.

This construction provides substantial and rigid guides for the several cross-heads of a three-cylinder locomotive.

The bars 14 tie the side guides and bearer 55 to the cylinder-head without extending the said guides, and enable the side guides to be removed for repairs without disturbing the cross-tie and cylinder-head.

I claim:

1. The combination in a three-cylinder locomotive, of a main frame; a cylinder structure; three guides; cross-heads mounted to slide on the guides; brackets on the heads of the cylinders, the central guide being directly attached to the bracket of the head of the central cylinder; and bars connecting the side guides to the brackets of the heads of the side cylinders.

2. The combination in a three-cylinder locomotive, of a main frame; cross-ties mounted on the frame; a cylinder structure having three cylinders; cross-heads for the cylinders; side guides for the side cross-heads, said guides being secured to the ends of the cross-ties; bars connecting the side guides to the cylinder structure; and a central guide secured to one of said cross-ties and directly connected to the cylinder structure.

3. The combination in a three-cylinder locomotive, of a frame; a cylinder structure having three cylinders and their valve-chests and heads for the cylinders, each head having a bracket; two cross-ties mounted on the frame and having overhanging portions; three guides of substantially the same contour, the side guides being secured to the overhanging portions of the two cross-ties; bars connecting one of said cross-ties to brackets on the heads of the cylinders, the central guide being attached to one of said cross-ties and directly attached to a bracket on the head of the central cylinder; and cross-heads adapted to the guides.

LAWRENCE L. NEEBE.
